Primary Examiner — Cathron C Brooks*Assistant Examiner* — Andrew T Nemeth(74) *Attorney, Agent, or Firm* — Finnegan, Henderson, Farabow, Garrett & Dunner LLP(57) **CLAIM**

The ornamental design for a display screen with user interface, as shown and described.

DESCRIPTION

The FIGURE is a front view of a display screen with user interface, showing the new design.

The broken lines of uneven length show the display screen and form no part of the claimed design. The broken lines of even length illustrate portions of the display screen with user interface that form no part of the claimed design.

The grayscale shading illustrates a contrast of appearance.
